Atty.

UNITED STATES PATENT OFFICE.

CLAUDE M. HERRINGTON, OF ST. LOUIS, MISSOURI.

PACKAGE.

1,390,784.

Specification of Letters Patent. Patented Sept. 13, 1921.

Application filed March 12, 1921. Serial No. 451,928.

To all whom it may concern:

Be it known that I, CLAUDE M. HERRINGTON, a citizen of the United States, residing at the city of St. Louis, in the State of Missouri, have invented certain new and useful Improvements in Packages, of which the following is a specification.

This invention is a shipping receptacle and has for its objects the provision of a package that will occupy only about one-half the space in return transportation when empty that it occupied when shipped full, and, furthermore, the provision of a package that is air-tight, secure, solid, and easily 15 and tightly closed.

This package is especially adapted for the shipment of lime or like granular material, and, especially, for such substances as are susceptible to deterioration under the 20 influence of moisture.

In the accompanying drawings forming part of this specification, in which like numbers of reference denote like parts wherever they occur,

25 Figure 1 is a vertical sectional view of one member of this package;

Fig. 2 is a top plan view showing a removable packing instrument in place;

Fig. 3 is a side elevation of the same;

30 Fig. 4 is a side elevation of one of these packages ready for shipment, loaded and with a combined packing instrument and insulation gasket in place; and

Fig. 5 shows the empty package knocked- 35 down ready for return shipment.

Transportation rates depend sometimes on weight, but, also, very generally on the amount of space occupied. For this reason, it is a great economy in business if a receptacle of a valuable kind that needs to be returned to the original shipper can be reshipped in knocked-down form, or nested relation so as to occupy less space.

The receptacle or package of this invention consists of a plurality of hollowed members 1, preferably in substantially the shape of a frustum of a cone. The said members are preferably formed of a light sheet metal, but may be of any material or strength and 50 of any size or shape.

Preferably each of the said members is provided with a bottom 2, carrying a flange 3 for attachment preferably within the lower edge of its member 1, although the encircling of the said edge by the said flange 3 is a permissible alternative consideration.

At the top of each of the members 1 is located an angle member, one arm 4 of which is attached either within or without the top edge of member 1, while the other arm extends as flange 5 for abutment with a similar flange upon the other coöperating member 1, completing the package. Bolts 6 and nuts 7 bind the two members 1 together to form a package such as shown in Fig. 4, 65 the said bolts passing through bolt holes 8.

In use both of the hollow members 1 will be loaded with the material that is to be shipped therein. Then the packing implement 9 or the packing implement 10 will 70 be laid on top of one of them. Then the one that the implement has been laid upon is inverted upon the other, the packing implement 9 or 10 serving as a lid to hold the material within the member 1 that is inverted while it is being turned over. Then in the case of implement 9, the same is withdrawn and bolts 6 inserted in place and the two members 1 bolted together. The package is then ready for shipment. When the 80 packing implement 10 is used, it may or may not contain bolt holes adapted to register with holes 8, and it may or may not be left in place between the two members 1 in the manner shown in Fig. 4. Whether intended 85 to be left there or not it serves as a lid while one of the members 1 is being inverted over upon its fellow. If left in place in the way shown in Fig. 4 it serves as a gasket to exclude moisture in any form. 90

When the loaded receptacle has reached its destination and is to be unloaded the nuts 7 are unscrewed and the bolts 6 removed. Then the contents of both members 1 is removed in any desirable manner. The 95 separated members 1 can then be nested as shown in Fig. 5 and transported wherever desired.

Snap fasteners, triggers, or other forms of catches or attaching means may be substituted for bolts 6 and nuts 7. 100

While Fig. 5 shows only the two members of one receptacle stacked together for return shipment, such members of several receptacles can be stacked together, in which event the relative saving of space in return shipment will be even greater than that stated above. Preferably, a long bolt will be used to bolt a plurality of these sections together for return shipment. 105

In using implement 9, its back end will be pushed against one of the bolts 6, and 110

then the nut 7 for that bolt will be somewhat tightened or nearly completely tightened before the implement 9 is withdrawn as hereinabove described.

5 Having thus described this invention, I hereby reserve the benefit of all changes in form, arrangement, order, or use of parts, as it is evident that many minor changes may be made therein without departing from 10 the spirit of this invention or the scope of the following claims.

I claim:

1. The combination in a package, of two hollow tapered elements having lateral opposed flanges at their large ends, a packing implement and gasket interposed between the large ends and flanges of said elements and separating the contents of one element from the contents of the other, said packing 20 implement and gasket having a handle dis-

posed laterally to the package and projecting an appreciable distance therefrom, and means detachably connecting the flanges and securing the packing implement and gasket between the large ends of the elements.

2. A package comprising a pair of cup-shaped members, reinforcing bands secured to the open ends of said members shaped to provide opposing flanges at said ends, a packing implement and gasket having a 25 body portion interposed between said flanges and a handle portion projecting laterally from the package, and means passing through said flanges and implement for securing the flanges together with the im- 30 plement clamped therebetween.

In testimony whereof I hereunto affix my signature.

CLAUDE M. HERRINGTON.
